EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

FILLING STOP-MOTION.

1,151,287.

Specification of Letters Patent. Patented Aug. 24, 1915.

Application filed September 10, 1914. Serial No. 861,146.

To all whom it may concern:

Be it known that I, EPPA H. RYON, a citizen of the United States, residing at Waltham, in the county of Middlesex and State 5 of Massachusetts, have invented a new and useful Filling Stop-Motion, of which the following is a specification.

This invention relates to a filling stop motion particularly adapted for use on weft 10 replenishing looms.

In looms of this type a thread cutter is provided to cut the ends of filling or weft which extend from the selvage as a bobbin 15 is being ejected from the shuttle and a full bobbin is being inserted therein.

It is the principal object of my present invention to provide a filling stop motion which may be applied upon the same side of the loom as the thread cutter above referred 20 to, and so constructed that it will positively assist in presenting the weft ends to the thread cutter.

With this object in view, my invention contemplates the provision of a filling stop 25 motion adapted to grasp the inserted weft, to bring it forward toward the thread cutter and to release the weft near the forward limit of its travel.

In carrying out my invention, I mount 30 the stop motion upon a movable support, one feature of my invention consisting in the provision of such movable support, together with operating devices by which it is caused to follow the movements of the 35 lay but on a reduced scale.

My invention further comprises certain devices, arrangements and combinations of parts which will be hereinafter described and more specifically pointed out in the ap- 40 pended claims.

A preferred form of my invention is shown in the drawings in which,

Figure 1 is a side elevation of my improved stop motion, together with certain 45 portions of the loom to which it is applied; Fig. 2 is a side elevation of certain of the parts shown in Fig. 1 but in a different position, and Figs. 3 and 4 are a side elevation and top plan view, respectively, of certain 50 parts of the stop motion drawn on an enlarged scale.

In Fig. 1 I have shown my improved filling stop motion as mounted upon a movable support made in the form of an upwardly

projecting arm 10 pivotally supported upon 55 a fixed stud 11 and adjustably connected to a cam lever 12 which extends into the path of a cam 13 mounted upon the usual cam shaft 14. The lay is indicated at 15 and is supported upon swords 16 in the usual manner. 60

The detecting portions of the stop motion comprise a grate 20 and a filling fork 21. The grate 20 is fixed to the end of the support 10 and is provided with an upwardly 65 extending flange 22 carrying a stud 23 upon which is pivoted the hub 24 of the filling fork 21.

The hub 24 is provided with a downwardly extending arm 25 carrying a laterally projecting pin 26. A spring wire 27 is secured to the support 10 in any convenient manner, as by the screw 28, and normally rests against a stop pin 29. The upper end of the spring 27 extends into the path of the 75 pin 26 and acts to yieldingly return the filling fork to the position shown in Fig. 3. Reference to said figure, however, will show that the spring 27 will engage the stop 29 before the filling fork reaches its extreme 80 lower position, so that, in its detecting action, the filling fork is actuated by gravity alone. The fork is thus capable of very sensitive action upon the inserted weft.

The hub 24 is also provided with an upwardly projecting arm 30 which extends into the path of a stud 31 supported in fixed position on a casing 32 within which a slide 33 is longitudinally movable. As the support 10 moves to the rear, the arm 30 en- 85 gages the stud 31, as shown in Fig. 2, and raises the filling fork against the resistance of the spring 27. When the support again moves forward, the filling fork gradually descends under the influence of the spring 90 27 and finally under the influence of gravity alone, as previously explained.

A forwardly extending horizontal arm 34 on the hub 24 acts as a dagger to engage a depending lug 35 adjustably secured to the 100 slide 33. The lug 35 is provided with a notch or recess 36 within which the point of the dagger is received when the absence of filling permits the filling fork to descend to the position shown in Fig. 3.

At its forward end the slide 33 is provided with a hook-shaped projection 37 which engages a rod 38 operative through

connections of the usual type, not shown, to release the shipper and stop the loom when the slide is moved forwardly.

The lug 35 extends downwardly a short distance below the notch 36, this extension being sufficient to engage the upper surface of the dagger 34 as the support 10 nears the forward limit of its travel, whenever the presence of filling prevents the cooperation 10 of the dagger 34 with the notch 36. The engagement of the extension of the lug 35 with the upper face of the dagger 34 causes the filling fork to be slightly raised, as indicated in Fig. 1, thus releasing the tension 15 on the filling as the lay and the support 10 reach their forward limits of movement.

The cam 13 is so adjusted that the lay 15 will begin its rearward movement before the beginning of the rearward movement of the 20 support 10. As the weft or filling extends from the selvage to the shuttle in the shuttle box, this movement of the lay carries the released filling beyond the end of the filling fork before the fork begins its rearward 25 opening movement.

Many of the advantages of my improved construction can obviously be secured if the grate is mounted upon the lay and only the fork is mounted upon the movable support.

Having thus described my invention, it will be seen that by mounting the filling stop motion upon a movable support, the movements of which correspond in general 30 to that of the lay but on a reduced scale, I am enabled to grasp the inserted weft and bring it forward into position to be seized by the thread cutter whenever the operation 35 of the thread cutter is desired, while at the same time I have provided means for releasing 40 the filling so that there shall be no interference with the continued operation of the loom except upon the failure or exhaustion of filling in the shuttle.

This form of stop motion is particularly 45 useful on automatic looms operated upon the drop box principle, as the usual types of filling stop motions cannot be used upon the drop box end of the loom, and furthermore they have been found to seriously interfere 50 with the action of the thread cutter when applied upon the opposite end of the loom.

Having thus described my invention, it will be evident that changes and modifications can be made therein by those skilled in 55 the art without departing from the spirit and scope thereof as set forth in the claims, and I do not wish to be limited to the details herein disclosed, but—

What I claim is:—

1. In a loom having a frame and a lay, a filling stop motion comprising a support movable relatively to said frame and lay, means for moving said support, a filling fork mounted on said support, and means 60 for giving said fork its detecting movement.

2. In a loom having a frame and a lay, a filling stop motion comprising a support movable relatively to said frame and lay, a filling fork mounted on said support, means for causing said support to follow the 70 movements of the lay on a reduced scale, and means for giving said fork a detecting movement as the lay and support move forward.

3. In a loom having a frame and a lay, a 75 filling stop motion comprising a support movable relatively to said frame and lay, means for moving said support, a filling fork and a grate mounted on said support, and means for giving said fork its detecting 80 movement.

4. In a loom having a frame and a lay, a filling stop motion comprising a support movable relatively to said frame and lay, means for moving said support, a filling 85 fork and a grate mounted on said support, means mounted on the loom frame for raising said fork, and resilient means for partially depressing said fork, the final detecting movement being produced by gravity 90 alone.

5. In a loom having a frame and a lay, a filling stop motion comprising a support movable relatively to said frame and lay, means for moving said support, a filling 95 fork and a grate mounted on said support, fixed means for raising said fork, and means for yieldingly depressing said fork to indicate the presence or absence of filling.

6. In a loom having a frame and a lay, a 100 filling stop motion comprising a support movable relatively to said frame and lay, a filling fork and a grate mounted on said support, means for causing said support to follow the movements of the lay on a reduced scale, and means for giving said fork 105 a detecting movement as the lay and support move forward.

7. In a loom having a frame and a lay, a filling stop motion comprising a support 110 movable relatively to said frame and lay, a filling fork and a grate mounted on said support, means for causing said support to follow the movements of the lay on a reduced scale, means for giving said fork a detecting movement as the lay and support move forward, and means for slightly raising the fork to release the weft as the support 115 nears its extreme forward position.

8. In a loom having a frame and a lay, a 120 filling stop motion comprising a support movable relatively to said frame and lay, means for moving said support, a filling fork mounted on said support, said fork being formed with a hub having an arm thereon 125 cooperating with a fixed stop to raise the fork as the support moves backward.

9. A filling stop motion comprising a sliding member, a movable support, means for moving said support, and a filling fork and 130

grate mounted on said support, said fork being mounted upon a hub having a dagger supported thereby in position to engage the sliding member when the weft is exhausted, and said member when moved forward being effective to stop the loom.

In testimony whereof I have hereunto set

my hand, in the presence of two subscribing witnesses.

EPPA H. RYON.
